Thawon & Thawon.

UNITED STATES PATENT OFFICE.

CHRISTOPHER E. WOOD, OF ROXBOROUGH, PHILADELPHIA, PENNSYLVANIA.

DOOR FOR GRAIN CARS.

Application filed September 30, 1921. Serial No. 504,281.

To all whom it may concern:

Be it known that I, CHRISTOPHER E. WOOD, a citizen of the United States, residing in Roxborough, Philadelphia, Pennsylvania, have invented certain Improvements in Doors for Grain Cars, of which the following is a specification.

This invention relates to improvements in doors for grain cars, the object of the invention being to provide a simple and economical device permitting the quick unloading of grain from box cars.

In the attached drawings:

Figure 1, is a fragmentary side elevation of the central door containing portion of a box car;

Fig. 2, is a fragmentary horizontal section of one side of a box car showing the outer car door;

Fig. 3, is a view in perspective of the retaining elements and the lower panel of a door made in accordance with my invention, and

Fig. 4, is a side elevation of a box car illustrating the door with the retaining elements removed.

It has been customary in forming the doors of box cars employed in the transportation of grain, to employ a series of boards or panels extending between and secured to the inside of the side uprights of the door frame, said panels extending across and blocking the door and being disposed one above another to the desired height.

This construction may provide an effective barrier, but some difficulty and a substantial loss of time is experienced in opening these doors to discharge the grain, the custom being to bash in the lower panels, which

operation entails not only the beforementioned substantial loss in time, but destroys the panels and their usefulness for any future use of a like nature. Doors of this type also on occasion have been found unsatisfactory owing to their tendency to spring leaks, with a consequent waste of the grain.

I have discovered means entailing no substantial increase in the material of the door which not only insures a perfectly tight and thoroughly efficient door, but also provides for a comparatively quick release of the grain from the car with no destruction of any of the elements of the door, these elements being capable of repeated use.

With reference to the drawings, my door

comprises a series of planks or panels of any number giving a barrier of the desired heights, said panels being indicated in the drawings by the reference numerals 1, 2, 3 and 4, and being secured across the door opening in the usual manner, preferably by nailing the ends of the panels to the inside of the uprights 7, 7, of the door frame.

Instead, however, of making the lower or base panel 4 of one integral piece, I divide it preferably at or near its center, and provide means for releasably retaining the abutting ends of the two panel portions 4^a and 4^b in place against the pressure of the grain within the car. This retaining means comprises an upright 5 secured to the outer faces of the panels and placed so as to overlap the abutting ends of the panel sections 4^a and 4^b, and as best shown in Fig. 1, it is preferred to secure this upright both to the panel sections 4^a and 4^b and to the overlying panels. To further reinforce the joint at the abutting ends of the sections 4^a and 4^b, I provide a key block 6, preferably having a groove 6^a in one side thereof for the reception of the lower end of the upright 5, which key block 6 is placed against the outer face of the upright 5 and, where the said groove is provided, against the outer faces of the abutting ends of the panel sections 4^a and 4^b, and is secured by means of nails or other securing means to the sill of the door. The key block 6 is preferably made of such width that it is closely confined between the outer face of the panel 4 and the inner face of the outer car door 8, as shown in Fig. 2, when the box car is provided with such outer door.

In releasing the barrier to permit discharge of the grain from the car, the operation consists merely of prying loose the key block 6 from the sill to which it is secured, and the consequent prying off from the face of the door of the upright 5, these operations being performed by means of a pinch bar or similar instrument and entailing no loss of time such as is found in the operation of opening the previously described commonly employed door. Immediately upon removal of the upright 5, the pressure of the grain within the car forces the two sections of the lower panel 4 outwardly at the center, thereby providing an opening through which the grain discharges.

It will be noted that in the opening of

this door, there is no destruction of the door elements, which accordingly can be used again. It will also be noted that the simplicity of the structure is little less than 5 that of the ordinary barrier, and involves no special construction of any sort.

The door has been subjected to the most grueling tests, and has been found to be absolutely efficient in retaining the grain in 10 the car, there being no leakage or any tendency of the elements to break out under the pressures from within or to work loose under the vibrations and stresses of travel.

I claim:

15 A knock down door for grain and like cars comprising upper and lower independent panels adapted to extend laterally across the door opening with their extremities behind the side posts of the door on

the inside of the car, said lower panel being divided into a plurality of longitudinal sections, a bar adapted to be secured to the outer face of the upper panel with its lower end overlapping adjacent ends of the lower panel sections, and a block adapted to be 20 secured to the sill of the door outwardly of and abutting the lower end of said bar to reinforce the latter in retaining the sections of the lower panel in position against pressure from within the car, the securing means 25 for both bar and block being such as to permit ready detachment of the said bar and block from the elements to which they are secured to release the sections of the lower panel and thereby to provide a dis- 30 charge opening for the contents of the car. 35

CHRISTOPHER E. WOOD.
